SLIDE LOOP BUCKLE

Carl E. Anderson, East Orange, N. J., assignor to
 Eastern Tool & Mfg. Co., Bloomfield, N. J., a
 corporation of New Jersey

Application November 13, 1945, Serial No. 628,015

4 Claims. (Cl. 24—195)

1

This invention relates to improvements in devices for securing clothing and other members together. While numerous devices have been proposed in this art for the attainment of that objective, such articles have generally been objectionable from the standpoint of being so complicated as to make it difficult to manufacture and use the same.

It is the object of this invention to provide a slide loop buckle which is of such construction as to make the application and use thereof to garments a matter of extreme simplicity. The device is so designed that the user may, in a minimum time, and by performing a minimum number of steps, secure together the desired parts of the garment in a simple and rapid manner.

The device is further designed to interlock the parts in use so that the slide loop buckle and parts secured together thereby will be precluded from accidental displacement, and, at the same time, may be manually disengaged in a rapid and facile manner, when so desired.

These and other advantageous objects, which will later appear, are accomplished by the structure shown and illustrated in the accompanying drawings, in which:

Fig. 1 is a top plan view of a slide loop buckle embodying my invention.

Fig. 2 is a bottom plan view thereof.

Fig. 3 is a vertical sectional view taken on line 3—3 of Fig. 1.

Fig. 4 is a transverse sectional view taken on line 4—4 of Fig. 2.

Fig. 5 is a perspective view of the loop frame member, viewed from the bottom thereof.

Fig. 6 is a perspective view of the slide member viewed from the bottom thereof.

Fig. 7 is a top plan view of the slide loop buckle of my invention showing a garment strap member passed therethrough in the first step of securing the strap to the slide loop member.

Fig. 8 is a similar view showing the strap passed through the slide loop member in the second step of securing the strap thereto.

Fig. 9 is a similar view showing the button of a bib positioned in the loop member in the third and final step of securing the garment parts to the slide loop buckle, and

Fig. 10 is a vertical, transverse sectional view, taken on line 10—10 of Fig. 9.

As shown in the drawings, the slide loop buckle of my invention comprises a rectangular frame member 11 having spaced parallel side portions or channels 12 and 13 interconnected at their

2

inner ends by a transverse channel having a bottom defining a transverse reinforcing bar 14, said side portions and bar member (see Fig. 5) being provided with flanges 15, 16 and 16' respectively, projecting therefrom and defining the inner walls thereof. Plate 17 connects the inner walls of flanges 16, 16' at the outer ends of the side portions 12 and 13 of the frame, said plate being angularly disposed relative to the plane defined by the said side portions and toward the free outer ends thereof and preferably terminating thereabove and therebelow. The plate 17 thereby presents an inner edge 18 disposed at a plane beyond that of the flanges 16 and 16' and an outer edge 19 in registry with the outer free ends 20 of the side portions 12 and 13 and disposed beyond the axial plane thereof. The plate 17 thereby presents an angularly disposed portion in the axial plane of movement of the slide member 42 shown in Fig. 6 when the parts are assembled (see Figs. 4 and 10). The side portions 12 and 13 of frame 11 are provided with extended arm portions 21 and 22 directed toward each other and converging forwardly and united as 25 at the apex 23 to define a generally triangular web portion, thereby defining, with the bar 14, a triangular portion 24 unitary with the end of the frame member 11 opposite the plate 17. The side portions 12 and 13 and arms 21 and 22 of the frame 11 are preferably marginally flanged to define an outer wall 25 co-extensive with said frame and directed at right angles to the axial plane of said side and arm members (see Fig. 5). The bar 14 is provided with a flange 26 directed 35 at right angles thereto and in spaced parallel relation to the flange 15. The web portion 23 of the slide loop frame 11 is provided with a medially recessed portion 27 extending almost to the outer wall 25 thereof for a purpose presently explained. The arm portions 21 and 22 are provided with inner flanged walls 28 and 29 (see Fig. 2) terminating at the recessed portion 27 of the web 23. The slide bar member 42, as shown in Fig. 6, is of generally rectangular outline, and is provided with a medial aperture C defined by the inner flange wall 32 of said bar. The bar is further provided with an outer free longitudinal edge 33 and with an angularly disposed wall 34 defining the other outer longitudinal edge thereof, said wall having flat portions 38, 39 and 40 of substantially uniform height with the inner wall 32 thereof. The outer longitudinal edge 34 of the slide bar is provided with serrations 35 intermediate the flat portions 38, 39 and 40 and protruding thereabove. The marginal ends of the slide bar

are curled and directed inwardly as at 36 and 37 to define marginal bearings to slidably engage the side portions 12 and 13 of the frame 11.

The flange 15 of the bar 14 and the flanges 16 and 16' of the side portions 12 and 13 of the frame 11 define, with the plate 17 connecting said flanges, an aperture A. The flange 26 of bar 14 defines, with the flanged walls 28 and 29 of the arms 21 and 22, an aperture B. As will be apparent from an examination of Figs. 5 and 6, the frame 11 and the slide may be blanked out of unitary sheets of material, such as metal, and cut, bent and formed as unitary members, which by virtue of the structure thereof above described, have great rigidity and may be economically made by the use of conventional tools and dies as will be apparent to those skilled in this art. The device may, of course, be manufactured from any other desired material and may be fabricated of a number of parts if so desired.

The slide member is mounted on frame 11 as shown in Fig. 1 so that, as shown in Fig. 4, the teeth 35 of the slide member are so disposed as to be in substantial axial alignment with the plate 17 medially.

The slide loop buckle of my invention is adapted for use in securing two members together, such as, for example, in securing a strap member to a bib member of a garment, as illustrated in Figs. 7-10. In the first step as shown in Fig. 7, the strap member is passed over the plate 17 of the frame 11 and under the slide bar, and threaded through the aperture C of the slide bar. The strap is next inserted intermediate the free outer longitudinal edge 33 of the slide bar and the bar 14 of the frame member 11, to project the strap through the aperture A of the frame member and beneath the triangular portion 24 thereof, as shown in Fig. 8. The bib or other member to be secured to the strap has a button 41 secured thereto; in the third step, the button 41 is passed through the aperture B and recessed portion 27 of the web portion 23 of the frame 11 (from the bottom thereof) as shown in Fig. 9. The bib is thus superimposed on the end portion of the strap as shown in Fig. 10 and conceals the same as will be apparent from Fig. 9, so that the appearance presented, in the use of structure of my invention, will be, as shown in Fig. 9, a neat and attractive one.

In addition to its function as a reenforcing bar, the bar 14 limits the extent of the aperture B and recessed portion 27 to also function as a locking bar or retaining means for the button 41.

When the strap is inserted in the slide loop buckle as above described, the toothed wall 34 of the slide member will wedge the strap intermediate the slide bar and the plate 17 (see Fig. 10). Any tendency of strap and bib to pull apart will simply serve to further lock the parts in the slide loop buckle against accidental displacement. At the same time, the parts may be readily manually displaced, when so desired, by moving the slide member in a direction away from the plate 17.

The teeth 35 of the slide member are shown in the drawings as being arranged in two spaced groups (see Fig. 6), that arrangement being preferable in order to accommodate the stitched portions of the strap either at the flat marginal portions 38 and 40 of the flange 34 (where the strap is provided with marginal stitching) or, where the stitching is along a medial axial line of the strap, the flat medial edge 39 of wall 34 of the

slide member intermediate the groups of teeth 35, will accommodate the same.

As will be apparent from the foregoing description, the slide loop buckle of my invention may be used with equal efficacy with strap members of various thicknesses. I have shown and described the use of my invention in the securing of a strap and bib member together; such showing is for the purpose of illustration only, and is not to be construed to limit the invention to such use as the device is obviously equally well adapted for use in securing other objects together.

Having thus described my invention what I claim as new and desire to secure by Letters Patent is:

1. A slide loop buckle comprising a frame member, having a pair of side portions and a bar connecting said side portions at one of the ends thereof, a plate angularly disposed relative to the plane defined by the side portions and secured thereto at the other of the ends thereof, a pair of arm members defining with said bar a triangular portion at one end of said frame, a slide member having an elongated median aperture and provided with marginally curled end portions slidably engaging said frame, and inwardly projecting serrations on the longitudinal edge of said slide member adjacent said plate and in coactive relationship therewith, whereby to engage an article positioned intermediate the frame member and slide to wedge the same against the plate of said frame.

2. A slide fastener comprising a frame member composed of parallel side channels, and a transverse channel connecting the parallel side channels, the transverse channel having a bottom defining a transverse reinforcing bar, all of the said channels having an inner wall and an outer wall, the side channel having free outer ends, a plate connecting the inner walls of the side channels and being angularly disposed towards the free outer ends of the side channels, the latter having extended arm portions converging forwardly to a medially recessed apex, a complemental slide member adapted to interfit with the frame member, the said slide member having a substantially flat slide body provided with marginally curled end portions slidably engaging said frame, the said slide body including an elongated medial aperture, a rear portion of the slide body defining a flange substantially perpendicular to the slide body, the said flange having a plurality of spaced series of teeth adapted to exert a clamping action with the angularly disposed plate of the frame member when said parts are closely juxtaposed, the said flange defining flat portions intermediate each series of teeth, whereby the teeth of the flange are adapted to clamp a strip of fabric inserted between the teeth and the angularly disposed plate at spaced intervals.

3. A slide fastener comprising a frame member composed of parallel side channels and a transverse channel connecting the parallel side channels and having a bottom defining a transverse reinforcing bar, all of the said channels having a substantially vertical inner wall, a substantially vertical outer wall, and a flat bottom, the side channels having free outer ends, a plate connecting the inner walls of the side channels and being angularly disposed towards the free outer ends of the side channels, the latter having extended arm portions converging forwardly to a medially recessed apex, a complemental slide member adapted to interfit with the body member, the said slide provided with marginally curled

end portions slidably engaging said frame, said slide member having an elongated medial aperture bounded by a continuous substantially vertical flange, a rear portion of the slide body defining an edge flange substantially perpendicular to the slide body, the said flange having a plurality of spaced series of teeth adapted to exert a clamping action with the angularly disposed plate of the frame member when said parts are closely juxtaposed, the said flange defining flat portions intermediate each series of teeth, whereby when the slide member is positioned operatively on frame member with the outer walls of the parallel side channels of the frame member inserted in the turned-up marginal edges of the slide member, and a strip of fabric to be fastened is passed between the teeth of the rear edge flange of the slide member and the angularly disposed plate of the frame member, and thence through the medial aperture of the slide member, thence around the free longitudinal edge of the slide member and between said edge and the inner wall of the transverse channel of the frame member, and the slide member is adjusted towards the angularly disposed plate, the fabric strip is 25 clamped between the teeth of the slide member and the angularly disposed plate.

4. A slide loop buckle comprising a frame member, having a pair of side portions and a bar connecting said side portions at one of the ends thereof, a plate angularly disposed relative to the plane defined by the side portions and secured thereto at the other of the ends thereof, a pair of arm members defining with said bar a triangular portion at the one end of said frame and a slide member provided with marginally curled end portions slidably engaging said frame, the longitudinal edge of said slide member adjacent said plate being in coactive relationship therewith, whereby to engage an article positioned intermediate the frame member and slide to wedge the same against the plate of said frame.
